UNITED STATES PATENT OFFICE.

ERNEST O. CARTWRIGHT, OF SPRINGFIELD, OHIO, ASSIGNOR OF ONE-THIRD TO LOUIS K. FISHER, OF DAYTON, OHIO, AND ONE-THIRD TO BYRON D. CAMPBELL, OF WEST MILTON, OHIO.

AUTOMATIC PRINTING-PRESS.

1,146,920.

Specification of Letters Patent. Patented July 20, 1915.

Application filed February 10, 1913. Serial No. 747,375.

To all whom it may concern:

Be it known that I, ERNEST O. CARTWRIGHT, residing at Springfield, in the county of Clark and State of Ohio, have invented 5 certain new and useful Improvements in Automatic Printing-Presses, of which the following is a specification.

This invention, which relates to the class of automatic printing mechanisms in which 10 is included a cylinder and a coöperating bed and automatic sheet feeding and delivery mechanisms, has for its object to provide an improved printing press of the general character stated, in which the several coacting 15 mechanisms that produce a completely organized automatic printing press are so designed, whereby the construction of such type of presses is simplified and cheapened, and a construction is provided including 20 parts coöperatively so connected that the same is capable of being operated at a great speed without excessive vibration and without the use of springs, cushions, or other shock absorbers, and in which the printing 25 mechanism proper is particularly adaptable for the automatic feeding and automatic delivery mechanisms combined therewith.

While my present invention, in its complete form, includes improved paper feeding 30 and improved automatic delivery mechanisms especially designed for coöperating with an improved cylinder and bed printing mechanism, and while for a proper disclosure of the construction, operation and advantages of my improved cylinder and bed 35 printing mechanism which forms the basic part of this application, I have shown in this application, so far as is necessary, to properly bring out the cylinder and bed 40 printing mechanism, the said sheet feeding and delivery mechanisms, I make no specific claims in this application for the said feeding and delivery mechanisms since they form the subject-matter of copending applications 45 numbered 747,377 and 747,378 filed on even date with this application.

One of the objects of my present invention is to provide a simple and effective means for suspending the printing operation, whereby to afford a practical and convenient adaptation therefor for their use in connection with the employment of automatic devices controlled by a mechanical feeder.

Another object of this invention is to pro-

vide certain improved mechanisms in a printing press of the character stated whereby to secure a better "register" or "timing" between the surfaces, respectively of the printing cylinder and the form on the bed 60 of the printing machine; to materially lessen the chance of frictional wear on the form to be printed from, and to enhance the quality of the product of rapidly operated printing machines.

With other objects in view, all of which will hereinafter appear, my present invention embodies the features of construction and combination of parts which are herein-after fully explained, specifically pointed 70 out in the appended claims and illustrated in the accompanying drawings, in which:

Figure 1 is a side elevation of my improved printing press, showing the same in its complete form with the automatic feed 75 and delivery mechanisms included. Figs. 2, 3 and 4 are fragmentary vertical sections of the machine, which combined on the broken lines 1—1, 2—2 form a central, vertical longitudinal section of my complete improved printing press. Figs. 5, 6, 7, 8, 9, 10, 11 and 12 are diagrammatic views of the cylinder and form bed devices of my improved printing mechanism which form the basic features of my present application, parts 85 thereof being in section. Fig. 13 is a detail diagrammatic side elevation of so much of the cylinder lifting devices as is necessary to illustrate the means for suspending the printing. Fig. 14 is a cross section of my 90 improved printing press taken substantially on the lines 14—14 on Fig. 1, looking in the direction of the arrow. Fig. 15 is a similar view taken on the line 15—15 on Fig. 1, on the line indicated by the arrow. Fig. 16 is 95 an enlarged detail section of the clutch shown in Fig. 14, by which the sheet feeding is suspended simultaneously with the suspension of the printing operation. Fig. 17 is a detail perspective view of the mechanism that actuates the paper grippers for the impression cylinder. Fig. 18 is a detail perspective view of a portion of the yoke that raises and lowers the impression cylinder. Fig. 19 is a detail perspective view 105 that shows one end of the main supporting shaft, and one of the eccentrics hereinafter referred to. Fig. 20 is a detail view of a portion of the sheet forwarding mechanism hereinafter explained. Fig. 21 is a side ele- 110

vation of that end of the machine on which is located the sheet pile elevator actuating mechanism. Figs. 22 and 23 are detail perspective views of the eccentric and pawl members that form a part of the said pile elevator actuating mechanism. Fig. 24 is a diagrammatic illustration of portions of the said pile elevating mechanism hereinafter explained. Fig. 25 is a partial plan view showing the sheet separating rolls clutch mechanism. Fig. 26 is a detail perspective view of one of the "initiators" hereinafter fully described. Fig. 27 is a side elevation of the mechanism comprising a part of the sheet separating devices. Fig. 28 is a detail perspective of the lower separating rolls clutch sleeve. Fig. 29 is a plan view, parts being omitted of the adjustable paper supporting fingers. Fig. 30 is a diagrammatic view that illustrates the paper feed action of the separating rolls. Fig. 31 is a detail sectional perspective view of the rear conveyer roll pivot. Fig. 32 is a detail sectional view of the "overthrow clutch" hereinafter described. Fig. 33 is a plan view of that end of the conveyer nearest the impression cylinder, parts being omitted. Fig. 34 is a section on the line 34—34 on Fig. 1, and particularly showing the form bed cam for actuating the arm 149. Fig. 35 is a detail plan view, partly in section, of the delivery board hinge.

The general arrangement of my improved printing press is such that the printing mechanism proper is located midway of the supporting framing in the manner and for the purposes hereinafter specifically explained, with the sheet feeding means mounted on one end and the sheet delivery mechanism upon the other end of the said framing, and it should be stated that in my complete press, best illustrated in Figs. 1, 2, 3 and 4, of the drawings, the several mechanisms are interdependently connected and operated from a main driving shaft and the intermediate or power transmitting mechanisms include certain timing devices whereby to feed up the sheet for being engaged by and connected with the impression cylinder at such predetermined times, as it, and the printing form assume their printing connections.

In describing the automatic sheet feeding and sheet delivery means, I shall go into the details thereof only so far as is necessary to connect them in their coactions with the printing mechanism proper that the operations of the said mechanisms may be clearly understood.

The framing of the machine, upon which the operating mechanisms are supported, may be of any suitable construction, but with the form bed thereof of sufficient length to allow a portion of its length to be beyond a point approximately in the middle of the

length of the machine when the form bed is at the limit of its travel in either direction, the said length of the form bed being sufficient to carry a rack along its full length, whose dimension is equal to one and one-half times the circumference of the cylinder. 70

Referring now to the details of construction, 1—1 designate a pair of round guide rods that extend the full length of the supporting frame and they are securely anchored onto the ends 2—2 of the said frame. 3 designates a bed mounted on the said rods that carries the printing chase or type form, and it, at one extreme end, the left, as shown, carries a cross or slide member 4, that is secured on the underside of the said form bed, and the said member has a socket 5 for receiving a crank pin 6 on a horizontally disposed crank wheel 7 located immediately below the said bed 3. Crank wheel 7 is suitably mounted on a fixed stud 8 on the supporting frame section 9, coextensive with the width of the framing of the machine and bolted to the said framing in such position that it affords clearance for the driving 85 and other shafts located below the same. 90

10 designates the main driving shaft from which motion is transmitted to all of the movable parts of my complete printing machine and a bevel pinion 11 on the shaft 10 95 meshes with and imparts motion to the crank wheel 7, the latter having a bevel gear rim 12 that receives the pinion 11.

At this point, it should be stated, that conventional construction in printing presses 100 having reciprocating beds drives the bed by some mechanism that moves the bed at a uniform speed to within a short distance of the reversing point at either end of its stroke, then slows it down some, and after 105 the reverse, propels the said bed with uniform velocity to the other end of the stroke, so as to make it possible to "time" its movement with that of a uniformly driven cylinder for at least a portion of its travel. Bed 110 movements of the character stated, so far as I know, all require shock absorbers of some sort.

The crank wheel 7 is held to its proper operative position on the stud pin 8 by the gib 13 on the wheel support 9, that lap over the said wheel and to further hold the wheel in a true-horizontal position and from wobbling I employ adjusting screws 14 that are mounted on the support 9 and engage 120 the wheel in a manner clearly shown in Fig. 2. For maintaining a desired lubrication of the crank wheel the said crank wheel 7 has an oil inlet 15 for leading the lubricant to the crank pin socket 16. 125

In my construction of the printing mechanism, which forms the essential feature of this application, the cylinder is driven by the form bed itself and partakes of the characteristic movement of the latter and the 130

coöperation of my cylinder devices and the form bed is such, that I have eliminated the necessity of an independent drive for the cylinder, as is usually required in cylinder and movable bed presses and further the necessity of springs or other aids to the reversal of the travel of the form bed is avoided, and all intermediate gearing or other devices to maintain the proper timing between 5 the surfaces of the printing cylinder and the form bed, as well as other complicated and expensive parts essential in the usual construction of cylinder printing presses, are eliminated.

10 To more clearly present the correlative arrangement of the impression cylinder, the bed with the printing form, and the crank mechanism that imparts the desired reciprocable movement to the bed and the corresponding reverse rotary movements to the cylinder, attention is now directed to Figs. 3 to 12 of the drawings. In each of the views referred to, 17 designates the reversely rotatable impression cylinder, which, in my 20 construction, includes a spur gear 18 that meshes with the rack 19 on the form bed 3 and the said gear 18 and the rack 19 are relatively of such dimensions, so that, when the cylinder is set at the position of taking 25 a sheet (see Fig. 5) approximately one-half of a forward revolution of the cylinder (which is effected by approximately one-third of the forward throw of the actuating rack bar) brings the front edge of the sheet 30 held on the front edge of the tympan in proper relation to the printing form on the bed (see Fig. 7); another one half revolution of the cylinder, presents the entire tympan surface of the said cylinder to the form, 35 constituting the printing operation and brings the cylinder to the position shown on Fig. 8; the third or final half revolution of the cylinder forward, then follows and during such revolution the front edge of the 40 printed sheet is projected within the range of the forwarding rolls, hereinafter referred to, so that the sheet may be taken care of by the offtake or delivery means hereinafter also explained; the cylinder now being in 45 the position shown in Fig. 9.

By reason of the horizontal crank drive for actuating the bed, it follows that as the crank reaches the limits or diametrically opposite dead centers of its rotation, the motion of the bed is materially slowed down 50 at the extreme points of its movement in opposite directions, by virtue of which excessive vibration of the movable parts is positively overcome without the use of shock absorbers and at the same time presents a 55 construction of printing mechanism especially well adapted for use in connection with my special form of automatic sheet feeding devices, since the timing of the 60 printing, the feeding and the delivering 65

mechanisms, synchronously operated from a common drive, can be accurately and practically determined.

For my form of printing means I prefer to use the gripping devices shown, for taking on and throwing off the sheet. These grippers, designated 20, may be the conventional rocker sort now commonly used, and they at predetermined times are thrown into and out of gripping positions.

By reason of the slow movement of the bed at the beginning of the movement of the bed forwardly, ample time is allowed for a positive setting of the grippers to their gripping position, the throw of the 70 said grippers to take on the sheet occurring while the cylinder is passing from position shown in Fig. 5 to that shown in Fig. 6.

The grippers 20 and the means for actuating them I have illustrated in a general 75 way, it being understood the grippers are rockably mounted and at times are oscillated to move into a gripping engagement see Figs. 6 and 7 and at other times swung back as is shown in Fig. 5 for example.

The gripper shaft has a crank extension, see Fig. 14, to engage, at times, with a pair of alternately movable plunger pins 21—21 actuated by pushers, each projected from a rock shaft that has a crank 23, as is clearly 90 shown in Fig. 17. Each crank 23 carries a pendulum rod 24, the lower ends of which pivotally connect with an oscillatory lever 25 that is engaged by the cams 26—26 driven from a movable part of the machine, as is 95 clearly shown in Fig. 1.

In order that the tympan on the cylinder be prevented from contacting with the printing form during the reverse movement of the latter, the cylinder is lifted a sufficient 100 distance, while the form moves in its reversed direction, whereby to provide a clearance between the surface of the form and the cylinder and yet maintain the meshing 105 of the cylinder gear with the form bed rack, so that operative contact between the cylinder and the form bed rack be not broken. The said lifting of the cylinder will be hereinafter more fully described, the same being 110 diagrammatically shown in Fig. 10,

which shows the cylinder as lifted approximately a distance from the root to the pitch line of the form bed rack, the pitch diameter of the cylinder gear meshing with the top of the rack teeth, thereby maintaining, as it were, a contact between the cylinder gear teeth and the rack of about one half the height of the gear teeth. In order that the tympan on the cylinder, as well as the fed sheet on the feed board, and also the 115 fenders for supporting the front edge of the printed sheet, as it leaves the cylinder, all hereinafter further described, be not disturbed during the reverse motion of the cylinder, supports at the front edge of both 120 125 130

the feed board and the delivery board are provided, and they are susceptible to vertical movement at times and in a manner presently explained. While the cylinder is thus held suspended, it is moved to the positions shown in Figs. 10, 11 and 12, the latter position being similar to the first or starting position indicated by Fig. 5, it being understood that after reaching the position shown in Fig. 6, the cylinder again drops to its printing position.

For raising the cylinder for clearance at the point of reversal of the bed and to suspend the printing operation when desired, I employ a novel cam and lever mechanism, the construction of which is best shown in Figs. 5, to 12 inclusive, by reference to which it will be noticed, the cylinder has concentric trunnions 27 journaled in housings 28 that form the upper end of impression yokes 29. The impression yokes 29 are slidably mounted in vertical guideways 30 in the machine frame and at a point approximately in the middle of the length of the said frame. The lower end of each of the yokes 29 has an elongated horizontal slot 31 to receive a laterally slideable box or bearing 32 and each of the said box bearings receives an eccentric trunnion 33 that is integral with a supporting shaft 34.

It should be stated, that after the cylinder has been raised through the upward swing of the eccentric trunnions 33, since the extent of the movement of the crank and the trunnion is very slight, just enough to raise the tympan from the bed form, the said relative positions of the cylinder and the co-acting elements is not changed sufficiently to render the eccentrics 33 susceptible to a reverse turn by the weight of the cylinder on the sustaining parts.

Referring again to the lifting of the supports of the feed and delivery boards as previously mentioned, attention is directed to the showing in Fig. 3 and the diagrams 5 to 12 inclusive. Upon shafts 137 and 164 driven by gears 139 and 165 from the driver gear 141, are cams 166, 167, the surfaces of which are engaged by roller bearings on the lower ends of lift rods 168, 169 which are vertically slideable in boxes on the inside of the framing 2 of the machine. The lift rods 168 engage the terminal of the sheet conveyer and the cam 166 which governs its vertical movement is so timed that when the cylinder 17 is about to receive a new sheet of paper as in Figs. 5 and 6, the conveyer terminal, together with its sheet supporters, drop into very close proximity with the tympan so that the grippers may readily grip the sheet as shown in Fig. 6. Having performed their functions the cams 166 continue their travel as shown in Figs. 7 to 12 inclusive, lift rods 168 and consequently the conveyer terminal and its depending parts

are raised and do not come in action again until a new cycle of printing operation begins, the lifting of the conveyer terminal and its parts having a two fold object, namely; that the sheet supporters herein-after noted as 109, may not interfere with the paper on the tympan after the grippers have taken it and that the sheet supporters will not strip the tympan packing from the cylinder surface on its reversal, which objectionable feature would be present were provision not made for its elimination. The action of the lift rods 169 is similar to the former but the purpose of their lowering is to bring the forwarding rolls 170 in register with the now printed sheet as indicated in Fig. 8, by which means, owing to the frictional contact, the sheet is carried within range of the delivery tapes and supplementary rolls 171 and carried to its destination. Cam 167 allows the forwarding rolls 170 and the tympan to remain in contact only long enough to dispose of the printed sheet as indicated in Figs. 8 and 9 when the parts are raised and act no more until a complete cycle of operation occurs and the press parts position themselves as in Fig. 8.

The lift rod and cam mechanism are produced in duplicate (one set on each side of the machine) as shown in Fig. 14.

At this point it should be stated that the supporting roll shaft 34 is journaled in both of the side frames of the press at a point directly below the center of the cylinder shaft and in proper relation to the guide rods on which the form bed travels and which extend from end to end of the press. The guide rods are, however, only of sufficient size to carry the weight of the form bed and other reciprocating parts without regard to the added burden of the impression during the operation of printing, since the co-operating parts are so related that the said added burden or strain is taken up by the said supporting shaft 34.

Referring now to Figs. 18, 19 of the drawings, it will be noticed the eccentric trunnions 33 serve to support the lower terminals of the impression yokes 29, the vertical oscillation of which is effected by the rotary action of the said trunnions 33 at predetermined times, which action is produced as follows: The extreme ends of the roll shaft 34, outside the eccentric trunnions 33, each have a smaller trunnion 35 concentric with the shaft and one of these carries a crank 36, which, through the action of a cam and lever device, presently described, oscillates the shaft 34 and its trunnions 33, and through the sliding bearing connection 125 raises and lowers the yokes 29 and the impression cylinder that is supported thereby. The cam and lever device, above referred to, that actuates the crank 36, includes a rocking arm 37, one end of which carries a roller 130

guide 38 that travels in a cam groove 39 on a gear body 40 that is driven direct from the main or drive shaft. Cam groove 39 has two diameters or sections that join with each other, the smaller one of which holds the arm 37 in the swung down position, see arrow 44 on Fig. 6 and consequently holds the impression cylinder down to the impression position during the required times, whereas the larger diameter portion of the cam groove 39 holds the said arm 37 to its swung up position, see arrow 52 in Fig. 10, and in consequence the cylinder to its elevated position, it being understood that the two cam sections are relatively such that the raising and lowering of the impression cylinder is properly timed with respect to the reciprocations of the bed or form. The connection between the rocker arm 37 and the yoke 29 is made through a lever 41 that is fulcrumed at its lower end on the forward end of the arm 37, and joins with a stud 42 that projects from the crank 36 mounted on the concentric trunnion 35 on the rolls shaft 34, it being readily apparent, by referring to Figs. 5 and 18 of the drawing that as the lever 41 is vertically oscillated, a limited sweep motion is imparted to the said crank 36 and hence the roller shaft is rocked and through its eccentric trunnions the yokes 29 are raised or lowered.

In automatic printing presses of the general type described, it is desirable that at times the printing operation be suspended and in my complete construction of press, I have provided a simple and efficient means for suspending the said printing operation and which is especially so designed that it can be easily operated by hand and at the same time affords easy adaptations of the use of my automatic devices controlled by a mechanical feeder. For such purpose, the lever 41 is formed with a right angled slot 43, the horizontal portion of which, under the regular running of the press, receives the stud 42 on the crank 36.

When it is desired to run off and suspend the printing operation, the lever 41 is swung over by hand from the position shown in Fig. 50 to that shown in Fig. 13, and assuming that the crank stud 42 is at its lowermost position and the printing cylinder at its down or impression position, the first upward impulse on the lever 41 will bring the said stud into the position shown in Fig. 13, in line with the vertical part of the slot 43, and free from being engaged by the further vertical movements of the said lever 41 until after it shall have been shifted back to its former position.

By reason of the peculiar construction and arrangement of the parts that have special reference to the printing mechanism, *per se*, I eliminate the "tracks" or "runways" commonly used for the support of

the form carrying bed in its travel and to sustain the impression during the printing operation, and I have provided in their stead a novel and effective means for securing a firm impressional contact between the printing cylinder and the form bed which means combine the support for the bed and the devices for raising and lowering the cylinder, accomplishing the desired result with a lesser number of parts than is usually required in similar printing mechanisms.

The under side of the bed 3, throughout its full length, has a plurality of strips 57 that serve as runners which engage the rollers 58 loose on the supporting roll shaft 34, clearly shown in Fig. 14.

In the practical arrangement of the co-operating parts described, the dimension between the center of the cylinder shaft and the center of the eccentric trunnion on the supporting roll shaft, is equal to the amount of the eccentricity of the trunnion, plus the radius of the supporting rolls, plus the thickness of the bed and its runners and plus the radius of the cylinder. By reason of such arrangement of parts, when the center of the eccentric trunnion is in a vertical line below the center of the supporting rolls shaft 34 the cylinder is "down", that is, in position for printing a form upon the bed.

When the crank 36 on the concentric trunnion of the supporting roll shaft 34 is acted upon in the manner previously stated, the said roll shaft 34 is rotated a certain distance, but still maintains its own central position with relation to its contact with the runners of the bed while the eccentric trunnions on the said roll shaft, acting through the impression yokes, raise the cylinder the required distance for clearness with the form on the bed.

One of the important advantages developed in the use of the structural elements referred to is, that there is no greater strain on the guide rods 1 on which the bed rises, during the impressional contact of the bed and the cylinder, than there is when the impression or printing operation is suspended since the added strain of printing is received by the supporting rolls shaft 34 and the shaft of the cylinder, and the said supporting rolls, at the same time, are free to rotate upon their shaft in the direction of the travel of the bed, with, of course, the added friction caused by the strain of the printing operation.

Referring again to the hand throw lever devices for suspending the printing operation, and particularly to Figs. 11, 12 and 13, it is apparent that by moving the connecting or hand lever 41, in the direction of the wide end of its angle slot, a surface in the slot is always presented to the underside of the crank pin, which insures the raising of the cylinder, while if the lever is allowed

to rest at the position where the upper surface of the slot is cut away, (the vertical part of the slot,) the lever will travel downward without bringing the crank pin with it. In this matter is the impression suspended.

As previously noted, my printing mechanism and power transmission means from a main drive shaft are so constructed and 10 combined, and their operations are so timed whereby to make their use especially adaptable for coöperating with a special construction of pile elevation and sheet feeding mechanism, which I shall now proceed 15 to describe.

Since the specific features of the pile elevator mechanism and the sheet feeding devices form the subject-matter of my copending applications, filed on even date with this 20 application, Serial Nos. 747,377 and 747,379 respectively, only so much of the said mechanism is shown in detail and will be herein described as is necessary to bring out the interdependence of the several mechanisms 25 and their generic coaction.

Upon a shaft 45 suitably mounted on the feed end of the press frame is adjustably mounted an eccentric 46 held to any of its 30 adjustments by a set screw, see Fig. 23, and at a point adjacent the said shaft, and journaled into both sides of the frame and somewhat below the normal height at which it is desired to keep the top of the pile of sheets, is another shaft 47, parallel with the shaft 35 45. Upon shaft 47, at the opposite inner sides of the frame are fixedly held sprocket wheels 48, of the smallest practical diameter, and at a point outside of the frame and near its end, the said shaft 47 carries a 40 toothed ratchet wheel 49.

50 designates a reciprocating pawl carrying arm, one end of which is revolubly mounted on the shaft 47, and the other end is fitted with a connection adapted to receive 45 one end of an eccentric strap 51, the other end of which is suitably mounted upon the eccentric 46 on the shaft 45 before mentioned. The ratchet wheel shaft 47 is also provided with a crank 53 for hand operation. A pawl 54 is mounted on the arm 50 for engaging the teeth of the ratchet 49, it being normally held out of engagement with the said ratchet by a spring 55, of just sufficient tension to hold the pawl out of operative 55 engagement with the said ratchet 49.

56 designates a hand released hold back pawl for engaging the ratchet 49.

At a convenient point at each side frame, I provide a stud 60 from which is suspended 60 a pair of guides or strips 61 of suitable material and these form guideways for trunnions on the ends of an elevator shelf that is mounted between the guides as shown. The studs 60 also afford fastening 65 for one end of sprocket chains 62, whose

free ends pass over the sprockets 48 at their respective sides, with their loose ends hung from the said sprockets unfastened.

The method of mounting the sprocket chains affords the effect of gearing to diminish the amount of lift the elevator would receive from a full tooth movement on the ratchet wheel, if the chains were connected directly to the elevator and admits of a smaller diameter in the ratchet wheel to afford the desired number of teeth.

At a point somewhat above the desired top of the pile of sheets, and at a convenient distance rearwardly of the forward edge of the pile, is frame 63 of light construction, 80 and it is hinged upon both of the side frames of the machine. One side of the frame 63 is positioned so as to be conveniently operated upon by a forwardly extended finger of a timing device, actuated from a driving part 85 of the power mechanism. This timing device, see Figs. 1, 21 and 24, and hereinafter more specifically referred to, normally supports the forward end of the hinged frame 63 and permits it to lower at predetermined 90 times. In the construction shown, the front end of the hinged frame is actuated by the extended finger 59 of one of a pair of levers 64, that carries a roller bearing 65 for engaging the timing device. On that side of the hinged frame 63, immediately above the ratchet wheel 49, is pivotally mounted a gravity lever 66, whose lower end is bifurcated to straddle the ratchet wheel shaft 47, and thereby be anchored against pendulous 95 motion, and the said lever is positioned between the machine frame and the ratchet wheel 49. The gravity lever includes an arc shaped abutment 67 having the radius of the ratchet wheel 49, and this said abutment extends approximately the width of the ratchet 49, it being of suitable length to practically house or cover the entire movement of the pawl 54.

68 designates a caliper rod that is pivotally suspended from the hinged frame 63 and extends the full width from side to side of such frame, it being mounted to follow the movement of the said hinged frame. Caliper rod 68 is made coextensive with 110 the width of the machine in order to be always in position for any size of sheets without regard to the position of the pile on the elevator.

For correct operation of the elevator, the eccentric 46 on the shaft 45 is set to operate at such time with the movement of the hinged frame 63 that the arm that carries pawl 54 is operated at the moment the hinged frame is "down."

The operation of the automatic pile elevating means is briefly explained as follows: A pile of sheets is placed on the elevator shelf and the latter, with the sheets, is lifted by the hand crank 53 on the ratchet wheel. 130

shaft, to bring the top of the sheet pile to the desired height, it being understood the hand released pawl 56 holds the ratchet against rotation in an opposite direction and supports the elevator. The caliper 5 rod 68 is set by means of its adjustable connections 69, at a position which allows the hinged frame 63 to suspend the gravity lever 66 at a point where the pawl 54 is just 10 out of engagement with the ratchet wheel while the caliper 68 rests upon the top of the pile of sheets while it is in the normal position and supports the hinged frame 63 while it is in its "down" position. 15 Upon the operation of the shaft 45 of the press, the pawl 54 makes its full movement out of engagement with the teeth on the ratchet wheel and it repeats that performance at each impulse or printing operation 20 until a sufficient number of sheets have been removed from the top of the pile by the separating mechanism to allow the caliper 68 to lower far enough to permit the gravity lever 66, through its arc portion 25 67 to press the pawl 54 into engagement with the ratchet teeth 49 so that the said pawl under its next drawing impulse, pulls the ratchet wheel over one or more teeth, as the adjustments may be, to restore the position 30 of the top of the pile. By moving the controlling eccentric 46, on the shaft 45 ahead or back, with reference to the timing of the hinged frame 63, a greater or less duration of the engagement of the pawl 54 35 with the ratchet wheel 49, may be taken advantage of, and the amount of lift of the elevator at each impulse, be governed for different thickness of material being fed. To lower the pile elevator, for renewal of 40 the pile or other reason, the same is readily effected by suspension of the pawls and the use of the hand crank on the ratchet wheel shaft.

The separating and sheet feeding mechanism.—As before stated, the printing mechanism hereinbefore described is more especially designed and its co-operative parts are so timed with respect to the main power shaft, to thereby adapt the said mechanism 50 for use in connection with my improved sheet pile elevating means, that forms the subject-matter of my copending application—Serial No. 747,379, and the latter mechanism together with the printing 55 means are so combined and interdependently connected, for co-operating with my improved sheet separating and feeding means that forms the basis of another one of my copending applications, Serial No. 747,377. 60 My improved sheet pile elevator devices and the sheet separating and feeding means are shown and described in this application to that extent necessary to make clear the operation of my complete printing mechanism 65 with my form of sheet pile elevating, sheet

separating and sheet feed or conveying devices.

My separating means generally includes frictional surfaces or substances for contacting with the top of the sheet pile and in such a manner that the top sheet is advanced at proper times to the feeding means that delivers it to the printing elements.

In my separating means I have particularly provided for encompassing the same in a relatively small space; to afford a greater degree of reliability in the separation of a single sheet from the top of the pile than usually is apparent in separators of that class to which my improvements relate; and for the utilization of timing devices with the separating and forwarding mechanisms arranged for synchronous action with the printing means and adapted for easy adjustment for working various sizes and qualities 85 of paper and other material.

Referring now to Fig. 4 it will be noticed a revolving shaft 77 extends transversely over the top of the pile of sheets to be separated, and it carries a plurality of members 70, 90 hereinafter termed initiators, since they initiate the separating of the top sheet from the pile, and deliver it to the main separating members in the nature of two (or more) sets of coacting rolls located in advance of the 95 top of the pile, and in position to receive between them, the top sheet or sheets advanced from the pile by the initiators 70. The initiators or members 70 each consist of a plurality of lever-like arms 71 fixedly 100 held on the shaft 77, but adjustable laterally and circumferentially thereon, by a set screw connection 72, as shown. The arms 71 include a spring controlled member 98 that carries a strip 73 of frictional material, 105 preferably rubber, and the said member is pivotally mounted on the pendent ends of the arms 71, whereby to provide for a yielding movement of the member 98 under adjusted spring tension to thereby provide a 110 resilient contact between the initiators and the top of the sheet pile, the strips 73 acting to wipe off the top sheet from the pile as the initiators, at predetermined times, are swung around with the shaft 77. Shaft 77 is journaled in a rocker frame 74 consisting of a pair of opposite side arms that are fulcrumed on a shaft 75 journaled in the side frames of the separator and into the rocker frame 74, and acts as a supporting pivot for 115 the said rocker frame. Shaft 75 is driven through a gear 76 on the main driving shaft 45 of the separator, meshing with a gear 78, on one end of the shaft 75 which shaft at the other end carries gear members 79—80, the former of which engages a large driving gear 81 on the shaft 77, the said gear 81 having a sweep arcuate motion on the gear 79 as the rocker frame is oscillated in the manner presently described.

- 82 designates a shaft whose ends are journaled in the opposite side arms of the rocker frame 74 and the said shaft 82 carries the upper separating rolls 83, it being driven by a gear 84 that meshes with the small diameter gear 79 on the shaft 75 that also engages and drives the gear 81. Gear 84 with the rolls 83 partake of the rocking motion of the rocking frame.
- 85 designates a shaft below and in vertical alinement with the shaft 82 and the said shaft carries the bottom separating rolls 86 that coöperate with the upper rolls 83 in the manner and for the purpose presently more fully outlined. Shaft 85 is journaled in the side frames 87 of the separating mechanism and at one end outside of the frame, it is provided with a clutch 88 for intermittent rotation, in a determined direction. Clutch 88 on shaft 85 includes a flanged sleeve 89 having projections 90 that serve as one member of the clutch; loosely rotating on this sleeve and lengthwise slidable thereon is a pinion 91 that meshes with the largest pitch diameter 80 of the double gear on the shaft 75. Pinion 91 includes a grooved hub with projections 92 on the face of the hub and serves as the other member of the clutch and for coacting with the opposing projections 90. The groove in the hub is the raceway for one arm of a controlling yoke 93 that is rockably mounted and has a forked portion for straddling the grooved hub. One prong of the yoke contacts with an angle boss 94 of see Figs. 20 and 27 mounted on a cross brace rod 95 in the rocker frame 74. The yoke 93 is normally pressed outwardly to release the clutch members, by a spring 96.
- Shaft 45 which acts as the main driving shaft of the sheet separating mechanism carries a large gear 76 that meshes with and imparts motion to a smaller gear 78 on the shaft 75, and with a gear 97 which through a sprocket or other suitable connection receives power from the printing mechanism drive. Shaft 45 on that end opposite the end having the gear 76 carries a cam device that consists of an inner disk 104 and an outer disk 99, one disk 104 being formed with a relatively long hub and the other 99, with a shorter hub, the long hub having a set screw connection for adjusting it on the shaft 45 and the other a similar set screw for adjusting it on the hub of the disk 104. A portion of the circumference of each of the disks is cut away to a desired smaller diameter.
- By using two disks and coöperatively adjusting them as stated, makes it possible to alter the circumference of both pitches of the cam and the adjustment relative to the shaft 45 to provide for the proper timing under different conditions which might confront the separating mechanism.
- 105 The brace 95 mounted in the rocker frame

74 carries a roller 100 that extends over the face of both cam disks.

It should be stated a similar means to that just described is also used for timing the forwarding roll of the conveying mechanism that coöperates with the separating means, and hereinafter more fully explained.

To provide for the proper and desired action of the separating means particularly the rolls 83, the pile of sheets is kept in perpendicular alinement with the wiping or receiving surface of the said separating rolls by means of a plate 101 pivotally suspended on the machine framing, as is best shown in Figs. 1 and 4, by reference to which it will be noticed along the top edge of the said plate 101 are a series of rod-like uprights 102 that have stud pintles for rotatably engaging sockets in the plate 101. The upper ends of the rods have flexible extensions bent to the proper radius to act as fenders 103 to keep the edge of the sheets from the contact with the lower separating rolls 86 and at the same time serve as supports for the sheets when pushed between the rolls for separation.

Since the rods 102 can be shifted laterally their fender portions 103 can be adjusted to different locations along the edge of the pile or with a view of overcoming buckling in the sheet, as it passes from the separating rolls onto the conveying devices.

The separating members, the upper rolls 83 and the bottom rolls 86 are each surfaced with some substance of great frictional quality, preferably rubber.

The forwardly feeding set of rolls 83, being the upper set in my present showing, are surfaced with a very soft clinging rubber, and located above the line of the plane of the top of the paper pile, and said rolls 83 are continuously rotated, at a predetermined speed, in the direction (forwardly) so that the sheet or sheets pushed beneath it by the initiators or feeders will be wiped or drawn from the pile. The upper rolls, as before mentioned, are carried by the rocking frame and are lifted at proper times by the cam devices before referred to and clearly shown in Figs. 20 and 27. The other or lower set of rolls 86 are surfaced with a substance of less frictional quality than that of the other rolls, and the said lower rolls are located immediately below the top set of rolls in such manner that the top surface of the said lower rolls is in a horizontal line with the normal top of the sheet pile.

The lower set of separating rolls is intermittently rotated at a speed somewhat greater than that of the top rolls and in the direction that the sheet or sheets pushed above it by the initiators would be driven back upon the pile see Fig. 30. The lower

set of rolls is secured by any suitable means against rotation in the (opposite) forward direction. The bottom rolls 86 are intermittently rotated as stated, by the rise and fall 5 of the top rolls 85 with the rocker frame 74 that carries the brace rod 95, on which is mounted the beveled clutch shifter 94 that engages the yoke 93 and moves it against the tension of its spring 96 and in consequence 10 connects the clutch members hereinbefore referred to and puts into action the drive for rotating the lower set of rolls only when the top rolls are in contact with them or with the sheet or sheets between the two 15 sets of rolls.

In the practical embodiment of the sheet separating means described, I have found that the frictional contact between the top rolls and the sheet beneath it, is greater 20 than the friction of the bottom rolls against the sheet between the rolls; and that the friction of the bottom rolls and a sheet in contact therewith is greater than the friction between that sheet and one in contact 25 with it and between the rolls. Hence, when a number of sheets are pushed between the rolls, the top rolls forward the top sheets in the direction of their travel, and the bottom rolls act successively upon the under 30 sheets as each is exposed to their surface, and not alone retard the forward slide of the said under sheets but return them in the direction of the rotation of the bottom rolls and in a direction reverse to the feed movement 35 of the uppermost sheet. Furthermore, the greater speed of the bottom rolls takes care of any varying number of sheets in order that all, except the top one are sent back onto the pile before the initiators make 40 their subsequent impulse, it being understood that the primary driving means that controls the action of the entire mechanism of my automatic press moves continuously and the timing devices that coat therewith 45 are such that the sheet separations are taken care of not alone for a delivery of a sheet to the impression cylinder at the proper time but also for a correct synchronous action with the pile elevating and conveying mechanisms that form a part of my 50 complete construction of automatic high speed printing press.

It should be here mentioned the timing cams 99 and 104 of the top rolls mechanism 55 are arranged to lift the top rolls off the sheets between the rolls before the end of the sheet with which they are in contact clears the sheet beneath it, else the top rolls would advance the contiguous under sheet 60 out of time.

The operation of the pile elevating and the sheet separating means briefly stated is as follows: The initiators start any number of sheets from the top of the pile of sheets; 65 the top rolls being still lifted and the bot-

tom rolls now being stationary; at the proper moment the lowering of the top rolls into contact with the sheets starts the bottom rolls in their revolution; the top rolls are then advancing the top sheet toward 70 its destination and the bottom rolls with greater speed are returning the under sheets to the top of the pile; at the predetermined moment, according to the physical condition of the material fed, the lifting of 75 the top rolls stops the rotation of the bottom rolls, and the mechanism referred to awaits the action of the initiators for the subsequent operation. If only one sheet should be advanced and presented to the rolls by 80 the initiators, the frictional advantage of the top rolls insures the advance of the sheet, while the bottom rolls have nothing to do.

To render my improved printing press of 85 a high efficiency, particularly as to speed and perfect successive feeding of the sheets from the pile, it is necessary that the top of the pile of sheets must be kept at an approximately uniform height with the line 90 of contact of the separating rolls.

So far as I know it has been somewhat of a problem in different types of sheet separators to provide the proper lift of the pile to accommodate the widely varying thickness 95 of material in commercial use.

To overcome the objections largely present in the common types of separators now in use and to adapt my pile elevating means for use in connection with the other elements 100 that go to make up my complete improved press is an essential feature of my invention.

For a proper coöperation of the printing mechanism *per se*, with the pile elevator, sheet feeding and separating devices hereinbefore described, I employ a special construction of sheet conveyer devices. These devices are described and illustrated in detail in my copending application filed on even date with this application Serial No. 110 747,276, and they are illustrated in this application to that extent that their generic relation to the printing mechanism proper and the other interdependently coacting mechanisms be fully and operatively understood. In presses of the front delivery and rapidly operated cylinder job printing kind, it is very essential that easy access may be had to the impression cylinder and other parts of the printing machine for the purpose of facilitating the rapid make ready and adjustments of the operating mechanism. In printing presses of the general type before mentioned, trouble is frequently encountered, during the operation of feeding or conveying the sheets toward the impression cylinder, by reason of the forward edge of the sheet turning or buckling up, especially when it is rapidly advanced and conveyed against the guides under a single im- 115 120 125 130

5 pulse of the feeding means actuated from the driving shaft. The bending back or buckling of the sheet, as stated, is caused by the air pressure against the front end of the forwardly progressing sheet. To overcome the objections before noted, I have provided a simple and effectively operating means for feeding the sheets by successive steps, that is, under intermittent progress 10 and for eliminating the back lash on the sheet caused by the action of the air as stated. Again, in my form of sheet conveying means a peculiar construction and arrangement of feed boards is provided that 15 may be quickly adjusted or moved and held out of the way of access to the cylinder without in the slightest disarranging the operative parts of the conveying or other mechanisms.

20 The conveying mechanism, about to be described, is especially designed for coöperat-

20 The conveying mechanism, about to be described, is especially designed for coöperating with the timing devices that regulate the different coactions of the other mechanism before described and in such manner that 25 all the desired functions of a sheet conveyer is accomplished with a lesser number of parts than is usual in mechanisms of like class.

like class.
In my press mechanism the working principle is based on the fact that it is necessary to move the sheets only a little more than its own width at each performance of the served machine, in order to serve the guides and grippers that form a coöperative part of the printing mechanism proper with another sheet on time.

In my conveying means is included a feed board 119 of a length between the guides and the separator equal to a multiple of the widest sheet within the capacity of the separator, plus an addendum for the pausing of the mechanism, such pause being for the purpose of positioning the sheet against the guides. The side frames 105 of the feed board terminate at their front end in a housing consisting of the opposite bracket irons 106 in which are supported a front guide shaft 107, the end guides 108 the sheet supports 109 and the front tape roll 110 all of which will be presently more fully explained. The other or inner terminals of the side frames 105 carry brackets 111 each formed with a hollow sleeve 112 journaled in the machine framing, said sleeves forming as it were, a hinge connection for the feed board 119, and the said sleeves also accommodate center pins 113 upon which the rear tape roll 114 revolves.

Referring now more particularly to Figs. 60 4 and 31 of the drawings it will be seen at a convenient point below the rear tape roll 114 is located a friction roll 115. Roll 115 is journaled at both ends into links 116 that are loosely fitted at one end on the driving shaft 117 of the conveyer. At the end in 65

proximity to the journals of the friction roll are a pair of levers 118 that work in a clearance space in the framing and are pendently suspended from a pair of oppositely disposed levers 64 pivotally mounted on the machine frame to swing in the vertical plane. On one end the driving shaft 117, adjacent to the link 116 has a wide gear 97 that meshes with a pinion 122 on the frictional roll shaft for driving the latter continuously. The conveyer driving shaft 117 carries an adjustable cam 123 see Fig. 24 which has for its purpose to raise the pivoted levers 64 that carry the friction roll 115 for holding such roll in contact with the tape roll 114 for a predetermined time, and then permit the said levers 64 to lower and thereby move the said roll 115 out of contact with said tape roll 114. In my complete printing machine mechanism the conveyer shaft 117 receives its motion from the served machine through a sprocket 130 in connection with an overflow clutch 131. This clutch, see especially Fig. 32 has but one point (indicated by 132) of engagement in order to preserve its timing with the served machine, such engagement comprising pin 120 pressed in place by a spring; and the overflow feature is taken advantage of to permit the conveyer to be moved by hand in its forward direction at will, as well as to prevent reversed motion of the power from backing up the conveyer. On the end opposite the sprocket wheel 130 the conveyer driving shaft 117 has a hand wheel 121 for advancing the conveyer without the power and to facilitate the handling of the sheets on the feed board. On a brace rod 133 between the levers 64 at a point above the tape roll 114 are adjustably supported, in jointed connections 134, a plurality of gravity rolls 135 that are held to always rest in contact with certain tapes of the said tape roll 114, the jointed connection of the said rolls 135 with the levers 64 permitting the rolls 135 to always gravitate against the said tape roll.

136 designates the endless feed tapes of the conveyer whose front ends take over the front tape rolls 110, and the said tapes travel close to the top surface of the feed board, 115 as shown.

Upon brace rods 138 mounted in the bracket bearings on the front end of the feed board are a series of sheet supporters or fingers 109 and these are laterally adjustable to give them the desired distance apart. Conveniently above the said sheet supporters 109 is mounted a rock shaft 107 on which a plurality of front guides 150 are adjustably mounted by the collar and set screw connections 140, shown. Rock shaft 107 at one end has a lever lug 124 and the said shaft with its lug 124 is rocked to the normal position by the coiled spring connection 125. An oscillating movement is imparted to the 130

shaft 107 at predetermined times by a lift rod 126, provided with a roller bearing 127 at the lower end that is normally held down to contact with a cam 128 by means of a spring 129, see Fig. 1. Cam 128 is located on one end of a cross shaft 137 that is suitably journaled in the machine framing and at that end opposite the cam it has a gear wheel 139 in mesh with a driving gear 141 on a hollow shaft 142 as best shown in Fig. 16, by reference to which it will be noticed that gear 141 has an integral sprocket wheel 143 over which takes an endless chain 144 driven from the sprocket wheel 145 on the drive shaft 212 presently again referred to.

146—147 designate a pair of transversely disposed rods endwise slidable in bearings in the housings 106, and these are arranged adjacent to and one at each side of the shaft 20 107 that carries the front guides 150. The ends of the rods 146—147 project beyond the housings and at one end they are connected by a centrally pivoted link 153 whose ends pivotally join with the said ends of the rods. 25 A coiled spring 148 mounted on one of the rods, is arranged so it maintains a certain normal position of the two rods 146—147 whose connection is such that as one rod is moved longitudinally in one direction the other rod is moved in the opposite direction, and vice versa. The rod 147 is adapted to receive a thrust movement in one direction from the served machine, by means of a vertically positioned rocker lever 149, that is actuated at predetermined times by a cam 30 151 on the form bed of the machine, see Fig. 34.

108—108 designate a pair of end guide members and they are adjustably mounted 40 for lateral positioning on the cross rods 146—147 and each guide 108 includes a pendant finger 152 for engaging the outer edges of the sheet as it is fed to the front guide.

By reason of the manner in which the 45 guides 108 are mounted, positive motion is imparted to the end of one rod and a like motion to the other rod, through the link connection 153, but in a direction opposite to the movement of the other rod, the guides 50 on both rods having a movement toward the center of the feed board, which affords the use of the end guides, on either side of the sheet fed to the front guides, without altering the movement of the rods.

55 One of the objects in constructing the guide devices so they receive their movements from means upon the served machine, is to make it possible to lift the feed board, together with its guides and other mechanisms carried thereby, away from its normal position and without disarranging the operative parts elevated therewith, and to restore it to its working position without having to make any adjustments or connections.

85 By reason of the manner in which my

feed board and its coöperating mechanism is arranged, it permits of readily lifting the said board high from the printing mechanism proper, giving easy access to the form and the rollers of a press, a great desideratum, providing as it were a feature not found in most automatic presses. The rear tape roll, hereinbefore referred to, is located closely adjacent to the separator used in connection with it and as the gravity rolls contact with the tape roll they receive and forward the sheet separated from the pile.

Briefly outlined, the operation of the conveying mechanism described is as follows: The timing cam 123 is set to bring the friction roll 115 into contact with the tape roll 114, see Fig. 30, simultaneously with the beginning of the separation of a sheet of paper from the pile by the separator; the said cam being also set to maintain this contact for 85 the desired time and then release. Rotation of the main shaft 117, causes the friction roll 115 to revolve the tape rolls 114, while the gravity rolls 135, in contact with the rolls 114, advance the sheet the distance 90 governed by the timing cams. Further rotation of the timing cam 123 or the main shaft 117 causes the frictional roll 115 to drop, the contact with the rolls 114 to be broken, and the tapes on the rolls to pause. Repeating 95 the operation, the first sheet is advanced to the front guides 150 where it is engaged by either of the end guides and properly centered to be engaged by the cylinder carried grippers during the pause of the tapes and 100 then taken away to make room for the following or next sheet. It should be here stated, that the cam 123 is usually set to continue the rotation of the tape rolls a little time after the sheet has reached the front 105 guides in order that the advance of the tapes after the sheet has come to rest against the front guides may serve to straighten up the front edge of any sheet that may be advanced out of proper alignment, see Fig. 33. 110 The end guides do not come into action for centering the sheet until the said sheet has finally come to rest against the front guides. After the end guiding of the sheet is done, the grippers of the impression cylinder close 115 upon the front edge of the sheet, the front guides are lifted by the oscillating movement of the shaft carrying them, and the sheet is taken toward its destination.

Referring to the coaction of the main 120 driving part of the printing machine, with the conveyer devices, by comparing Figs. 15 and 16, it will be noted that at such time as it may be desired to suspend the printing operation of the machine it is only necessary 125 to shift the lever 41 as previously described and shown in Fig. 13. In order to suspend the sheet feeding functions simultaneously with the suspension of printing the following provision has been made; contacting the 130

lever 41 (see Fig. 14) is a beveled disk 154 which is positioned on a transversely extending rod 155, a spring 156 encircling same with the object of keeping the aforesaid rod 155 pressed outwardly and also to keep the long clutch pin 157 on a yoke 158 on the end of rod 155, in normal engagement with the clutch pin 159 integrally formed with the gear 143 and its hub. Pin 157 slidably engages one of two openings 160 in a second sprocket 161 over which a chain 162 rolls, connecting sprocket 161 with sprocket 130 on the conveyer shaft. By this means while engagement is had between the aforesaid parts, motion is imparted to the sheet feeding devices but when lever 41 is thrown over to suspend the printing operation, rod 155 is forced back by reason of the contact thereof with the beveled face 154, yoke 158 and its depending clutch pin 157 and guide pin 163 are withdrawn so that further rotation of sprocket 143 has no effect on sprocket 161, the connection being broken.

In the complete embodiment of my automatic press, is included a sheet retarding delivery mechanism in which the actuating means including power transmission are driven by the main power shaft of the press from which power is transmitted to all the interdependently operating parts of the complete press. While my sheet retarding mechanism is designed for special adaptation with the printing, conveying and sheet controlling means, hereinbefore described, the same *per se*, forms the subject matter of my copending application filed on even date with this application, Serial No. 747,379. In the present case, so much of the said sheet retarding delivery means is illustrated and will be hereinafter described, as is necessary to clearly set out the operation of that part of my complete automatic press and the advantages of the same.

In the construction shown means is provided for intermittently arresting the dropping of the printed sheets, and finally depositing the said sheets, repeating the arresting function as many times as may be necessary or desired, before the sheet is finally allowed to rest on the printed pile.

172 designates the main offtake or endless tape carrier that takes the printed sheet as it is delivered from the printing cylinder and 173 is a sheet discharging or delivery board from which the single sheets pass onto the sheet retarding and delivery devices, the general construction of which is best shown in Fig. 2 of the drawings, to which special reference is now made.

60 The retarding means broadly include means for intercepting the traveling printed sheet, a plurality of times and dropping it by gravity from one position to another and finally depositing it. The retarding means stated include a series of horizontally

disposed and longitudinally reciprocated toothed or pronged supporters, hereinafter termed "fliers." The "fliers" are arranged in pairs, each pair comprising a set consisting, preferably of a plurality of fliers, three being shown, as constituting each set. Each set of "fliers" includes a series of cross bars that extend transversely of the delivery end of the machine. One set of cross bars 174 are fixedly secured at one end to a traveling head 175 slidably held and guided between the rails 176 that constitute a part of the side frame 2, the other set of cross bars 177 being likewise secured to and projected from a like traveling head 178 slidably mounted on the rails 179 of the opposite frame, as is clearly shown in Fig. 1. Each of the bars 174-177 form the supporting means for the sheets and at the same time act as interceptors, since they intermittently hold and retard the delivery of the printed sheet after it is discharged from the hinged delivery board 173.

The sheet supporters or "fliers" include a desired number of finger rods or prongs 180 and 181 fastened into and at right angles to their respective cross or head bars from which they extend in the horizontal plane, and each of the said prongs 180-181 has its outer end curved upward to such an extent as will not interfere with their clearance with the "flier" next above in the assembly of "fliers." The upward projection of the prong ends provides for giving the forward edge of the sheet an upward deflection as the "flier" is drawn under it, thereby lessening the likelihood of the sheet sagging at that point when the front ends of the "flier" prongs are in vertical alignment in the progress of the stroke.

The "fliers" are of like construction, and they are relatively mounted so that in one sliding housing the "fliers" are mounted higher up in relation to the guideways than in the opposite housing, so that when the two housings are assembled in the machine the "fliers" in one housing will clear between the "fliers" in the other housing in their horizontal travel. The longer dimension of the "fliers" is such that the free ends of the ones on one side will clear the housing on the other side as they pass during the travel of the slides. The shorter dimension of the "fliers" is sufficiently greater than the dimension of the maximum sheet to be carried through to prevent the dropping of the front edge of the sheet should the "fliers" stop or pause halfway of their stroke, as is liable to be the case with the promiscuous stopping of the printing mechanism.

182 designates a toothed or barred rake, the head 183 of which extends transversely of the machine, and is located at a point immediately in front of the supporting bar 130

- of the "fliers" when the machine is at its maximum stroke forward, that is, on the side of the bar from which the prongs project, the said rake 182 being suspended in a 5 vertical plane, projecting downward a sufficient distance to act as a guide for the rear edge of the sheets as they drop from one "flier" to the one beneath and also after it has left the lowermost "flier." 184 designates a second toothed or barred rake, and the said rake includes a head in the nature of a cross bar 185, the ends of which are rockably mounted in bearing boxes 186 shiftably mounted on arms or brackets 187 10 hingedly connected at their rear ends on the side bars of the frame, as at 183a. Boxes 186 are held to their adjustments on the arms 187 by the clamp screws 188 and the bar 185 is held to its rocked adjustments by 15 the screws 189. The prongs 190 on the front rake act as guides for the front edge of the sheet as it is intermittently dropped and for the front edge of the pile of sheets, as shown.
- 20 At the proper point in the rear of the "flier" assembly is a cross shaft 191 journaled in the side frame members and adapted to receive motion from the printing cylinder shaft, through the chain 192 that takes over a sprocket 193 on the cylinder shaft, a sprocket 194 on the shaft 191 and over an idler 195, as shown, it being obvious that as the impression cylinder is oscillated through the connections with the form bed the shaft 25 191 is oscillated with a half revolution in each complete printing movement of the press. At each end of the shaft 191 is a crank 196 of a proper eccentricity to accomplish the full movement of the "fliers." 30 The said cranks are set diametrically opposite each other, each being connected to the connecting rods 197 that pivotally join with the sliding housings on their corresponding side of the machine. In each of the upper 35 40 end frame members, above the shaft, is a removable bearing 198, encompassing a hollow sleeve 199, as is best shown in Fig. 1, which constitutes one terminal of the supporting frame of the delivery board 173 which extends from the pivotal point to the point in the delivery where the "fliers" come to pause at the forward end of the stroke.
- 45 On the sleeves 199 are pivotally mounted the terminal hinges of opposite ends of the delivery board 172 that receives the printed sheet from the press.
- 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

which the printed sheet is delivered from the impression cylinder, is a freely revolving tape roller 203 connected by endless tapes 204 with and driven by the main tape roller 201. At the forward end of the other delivery board, at the parting point of the "fliers," is suitably mounted another freely revolving tape roller 205 connected by the endless tapes 206 and rotated by the main tape roller 201.

70 By reason of supporting the first and second delivery boards in the manner described and shown provides, as it were, a ready removable delivery conveyer since both boards can be swung up and readily sustained at 80 their elevated positions, thereby providing for easy access to the press mechanism with a minimum expense of time and energy, it being also apparent that by hinging the delivery boards and driving the tape rollers 85 from a central point, the mechanism can be folded up at will without disturbing the adjustments or position of the parts.

75 The operation of delivery and the retarding means briefly stated is as follows: The 90 tape roller 201 is given the proper speed to time the travel of the sheet from the impression cylinder to the topmost of the "fliers" in order that each time a "flier" is moved to a receiving position there will be a sheet 95 to come upon it. At each complete performance of the press the "fliers" make a complete reciprocation, that is, the topmost "flier" and the companion "fliers" of the set including the topmost "flier" change 100 places with the several "fliers" that constitute the other set of "fliers" and then restored to the original position. It will be remembered that the front ends of the teeth or prongs in the "fliers" are free, and that 105 the end of the "fliers" opposing the housing in which they are fastened are free, and the two rakes or barred members are adjusted for the proper width of sheet going through. Where the impression cylinder 110 presents a sheet to the delivery tapes, the forwarding motion of the latter advance the sheet and propel it into the space above the topmost "flier" with the front edge of the sheet against the forward rake or barred 115 member, and the rear edge of the sheet near the rear rake or barred member. The topmost "flier" is drawn from under the sheet at the time the "flier" next below is projected under it, and at the next operation 120 of the press the top "flier" is presented to receive the printed sheet, while the previous sheet is dropped to "flier" No. 3. At the next operation, by repetition, the first sheet drops to No. 5, the second to No. 3, and the 125 third to the topmost "flier."

I do not wish to be limited to any specific number of "fliers," as it will be seen that each pair of "fliers" suffices to retard the progress of the sheet through one complete 130

performance of the press and it is a matter of choice within the scope of the invention and the desired result just how many pairs are used.

5. In order to properly support the sheet in the delivery, and present the topmost "flier" for the receipt of each sheet as it comes from the press, the "fliers" which I designate by the even numbers as 2, 4 and 6, are employed, and the action of the sheet in regard to them is the same as in regard to the others, except that it occurs at the opposite reciprocation from that of the odd numbered "fliers."
10. The object in having the forward rake or barred member hinged in the manner suggested is to permit the sheets to be easily removed from the delivery pile by raising it pivotally suspended, it still acts as a guide for the forward edge of the sheets between the "fliers" even if lifted sufficiently to uncover the front edge of the delivery pile.
15. 213 designates the ink font.
20. The means employed for inking the form in my machine may be of any suitable character with the exception that in my construction I use a pinion 207 fastened to the removable trunnion on one end of each of the form engaging rollers 208. The pinions 207 mesh with the rack on the form bed see Fig. 3, while the trunnions 214 ride in the bearers 209 and thereby accomplish the drive of the rollers 208 independent of their frictional contact with the bed form and without the use of an intermediate pinion between the rack and the vibrator devices for the ink rollers 208.

- In the drawings (notice Fig. 1) I have indicated the vibrator devices as comprising generally a bell crank lever 210 that joins with an arm of an eccentric 211 mounted on the driven shaft 212 that carries the gear body 40 hereinbefore referred to; as the means for vibrating, the ink rollers are of the conventional type, further description and illustration thereof is deemed unnecessary.

- From the foregoing description taken in connection with the accompanying drawings it is believed the details of construction of my improved printing mechanism, the operations of the distinctive parts thereof and the coöperation of the said distinctive parts of the press, and their advantages have been sufficiently disclosed that those skilled in the art will readily understand the same, and hence a further detailed description of the complete operation is deemed unnecessary, other than to mention, that after placing the pile of sheets to be worked up on the pile elevator and adjusting the pile to the proper position, and then starting the driving power, the sheet is automatically handled throughout its passage

through the machine until it is finally deposited on the printed pile, since the separating mechanism takes off a sheet from the pile, and discharges it onto the conveyer, where it is automatically set to proper end and crosswise alinement to the front guides, is then taken up by the printing mechanism and discharged onto the delivery and in its final movement it is retarded sufficiently to permit the inked face to dry before it is deposited on the printed face of a previously printed sheet.

No manual adjustments or manipulation of any kind is required during the running of the press, the adjusting of the parts, particularly the timing devices and the transmitting means being all adjusted to suit the character of the sheet to be worked up before the press is started to do its desired work.

What I claim is:

1. In a printing press, a reciprocatory form carrying bed, a rotatable impression cylinder coöperatively mounted above the bed to normally lie with its impression face against the form on the bed, coöperative means for imparting reciprocation to the bed and simultaneously turning the cylinder, sheet feeding means that deliver the sheets to be engaged by the cylinder, and means for relatively moving the bed and the impression cylinder apart and simultaneously stopping the sheet feeding means without stopping the movements of the cylinder and the reciprocating bed, said means including a reciprocating lever and a crank connected with the said lever, the said lever having provision for operatively connecting and disconnecting with the said crank according as the said lever is in one position or another.

2. In a printing press of the character described and in which is included a reciprocatory form bed, an impression cylinder driven by and reversely rotated by the reciprocatory movement of the form bed and means for lifting the cylinder from contact with the form bed, such means including vertically slidable yokes in which the cylinder is journaled, eccentrics for raising and lowering the yokes, a crank positively connected to one of the eccentrics, cam and lever devices for shifting the crank for moving the eccentrics to raise or lower the yokes, said cam and lever devices including a hand shifted member having a right angled slot, the crank on the eccentric having a pin for engaging the horizontal portion of the slot when the hand shifted member is at one of its adjustments whereby to form a positive connection between the crank and the cam and lever devices, and under another adjustment of the hand shifted member to move freely in the vertical portion of the slot in the said hand shifted member.

3. In a printing press of the character described, a reciprocating form bed, an impression cylinder carrying sheet grippers, the said cylinder normally having its impression surfaces in contact with the form, means coöoperating with the cylinder and bed for imparting reverse rotary movements to the cylinder as the bed reciprocates, other means for holding the cylinder lifted from the form while the said cylinder is making its reverse rotation relatively to the said form, a paper feeding means, sheet stops rockably mounted adjacent the upper paper receiving surface of the cylinder, and further means for rocking the sheet stops to free the sheet and immediately afterward actuating the sheet grippers to take the freed sheet, and a forwarding roller normally engaging the top of the cylinder for advancing the printed sheet, and means for elevating the said roller as the grippers pass into position to engage a new sheet.
4. The combination of a cylinder having trunnions, impression yokes having bearings to receive the said trunnions, vertical guideways for the said impression yokes, a reciprocating bed, guide rods for the bed, a supporting roll shaft with which the said bed engages, eccentrics carried by the said shaft, and connections between the said eccentrics and the said impression yokes by virtue of which the said cylinder is raised and lowered relatively to the bed.
5. The combination of a cylinder having trunnions, impression yokes having bearings to receive the said trunnions, vertical guideways for the said impression yokes, a reciprocating bed, guide rods for the bed, a supporting roll shaft with which the said bed engages, eccentrics carried by the said shaft, connections between the said eccentrics and the said impression yokes by virtue of which the said cylinder is raised and lowered relatively to the bed, and continuously acting power transmitting and translating connections between the said bed and cylinder.
6. The combination of a cylinder having trunnions, impression yokes having bearings to receive the said trunnions, vertical guideways for the said impression yokes, a reciprocating bed, guide rods for the bed, a supporting roll shaft with which the said bed engages, eccentrics carried by the said shaft, connections between the said cylinder and the said impression yokes by virtue of which the said cylinder is raised and lowered relatively to the bed, continuously acting power transmitting and translating connections between the said bed and cylinder, and means forming a coöperative engagement between the said bed and cylinder for taking up lost motion in the said power transmitting and translating connections.
- 66 7. In a printing press, a supporting frame,

a reciprocable bed, longitudinal guide rods for supporting the bed, a supporting roller shaft transversely mounted beneath the bed and on which the bed rests, a rotatable impression cylinder mounted on the frame with its axis over the axis of the said shaft and co-operating connections between the said shaft and the said cylinder for moving the said shaft and the cylinder relatively toward and from one another relatively to effect the impression, and means for rotating the cylinder as the said bed is reciprocated.

8. The combination of a cylinder having trunnions, impression yokes having bearings to receive the said trunnions, bed guideways for the bed, a roller carrying shaft with which the said bed engages, the said shaft being located directly beneath the aforesaid cylinder, eccentrics carried by the said shaft and connections between the said eccentrics and the said impression yokes by virtue of which the said cylinder is raised and lowered relatively to the bed.

9. In a printing press of the character described, the combination with the opposite side portions of the framing and the cylinder having trunnions, the said cylinder being transversely mounted with respect to the said side portions of the framing; of a cross shaft whose opposite ends are journaled in the side portions of the framing, roller bearings on the said shaft, the said shaft being located directly below the center of the cylinder, a reciprocating bed that rides upon the roller bearings of the cross shaft, an eccentric on each end of said shaft, bearing yokes in which the trunnions of the impression cylinder are journaled and connections between the said yokes and the eccentrics for moving the yokes to bring down the cylinder upon the bed and for lifting the cylinder from the bed after the impression is made.

10. The combination of a cylinder having trunnions, impression yokes having bearings to receive the said trunnions, guideways for the impression yokes, a reciprocating form bed, a roller carrying shaft upon which the said bed travels, the said shaft being located directly beneath the said cylinder and rotatably mounted on the press frame, eccentrics carried by the shaft and connections between the said eccentrics and the said impression yokes by virtue of which the said cylinder is raised and lowered relatively to the bed.

11. The combination of a cylinder having trunnions, impression yokes having bearings to receive the said trunnions, vertical guideways for the impression yokes, a reciprocating form bed, a roller carrying shaft upon which the said bed travels, the said shaft being located directly beneath the said cylinder and rotatably mounted on the press frame, eccentrics carried by the shaft and connections between the said eccentrics and

the said impression yokes by virtue of which the said cylinder is raised and lowered relatively to the bed, said connections including means for rotating the shaft at times to raise and lower the yokes and the said cylinders with respect to the form bed.

12. The combination of a cylinder having trunnions, impression yokes having bearings to receive the said trunnions, vertical guide-
10 ways for the impression yokes, a reciproca-
tory form bed, a roller carrying shaft upon
which the said bed travels, the said shaft
being located directly beneath the said cyl-
inder and rotatably mounted on the press
15 frame, eccentrics carried by the shaft and

connections between the said eccentrics and the said impression yokes by virtue of which the said cylinder is raised and lowered relatively to the bed, said connections including means for rotating the shaft at times to raise 20 and lower the yokes and the said cylinder with respect to the form bed, said means in-
cluding a trunnion on one end and concen-
tric with the rotary shaft, a crank fixedly
connected to the said trunnion and a lever 25
device for actuating the crank.
